EUGENE C. HERTEL, OF CHICAGO, ILLINOIS, AND EDWARD W. ISOM, OF LOCUST VALLEY, NEW YORK, ASSIGNORS TO SINCLAIR REFINING COMPANY, OF CHICAGO, ILLINOIS, A CORPORATION OF MAINE

CRACKING OF OILS

Application filed January 7, 1925. Serial No. 966.

This invention relates to an improved method and apparatus for cracking heavier hydrocarbon oils for the production of lighter and lower boiling hydrocarbon oils, such as gasoline or pressure distillate. More particularly, the invention relates to an improved method of operating circulatory pressure stills provided with reflux towers. The invention includes an improved method of distilling hydrocarbon oils under pressure and an improved apparatus for use in carrying out such pressure distillation.

When heavy hydrocarbon oils are distilled under pressure, they are "cracked" with the production of lighter oils. The products of the cracking reaction also include incondensable gases, and carbon or coke, or heavy tar. In the commercial operation of a pressure still, some definite product or group of products, e. g. gasoline or pressure distillate, is usually desired, but the vapors escaping from the pressure still itself may include heavier constituents in addition to the constituents desired in the pressure distillate; and, in some cases, particularly in the distillation of lighter charging stocks, the escaping vapors may include vaporized constituents from the charging stock in their original condition. To the extent that such constituents, heavier than are desired in the pressure distillate, can be decomposed in the pressure still with further production of desired pressure distillate constituents, it is desirable to return such heavier vaporized constituents to the pressure still for further treatment therein.

In cracking gas oil character charging stock, for example, for the production of gasoline by distillation under pressure, the vapors escaping from the still may include, in addition to the desired gasoline constituents, heavier kerosene vapors or vaporized constituents of a light gas oil character. If returned to the pressure still, such heavier constituents may be subjected to further cracking treatment with the production of additional quantities of the desired gasoline constituent, whereas if they are condensed with the gasoline constituents, further fractionation treatment of the pressure distillate

is required to separate the desired gasoline product. In cracking a light gas oil, or charging stock including kerosene character constituents, for the production of gasoline, lighter constituents of the charging stock may be vaporized before they are cracked, and these vapors may also escape with the desired gasoline constituents from the pressure still.

According to the process of the present invention, such constituents of an intermediate character as are not desired in the pressure distillate and as can advantageously be subjected to further treatment in the pressure still are returned to the pressure still for further treatment therein by an improved method of operation. The invention also includes an improved arrangement of apparatus for refluxing and returning such intermediate character constituents for further treatment in circulatory pressure stills.

According to this invention, vapors from the pressure still are subjected to a refluxing operation, and the reflux is positively returned to the circulating stream of oil in the still in a manner to insure its subjection to the cracking conditions maintained in the still before any of the constituents of the returned reflux can again escape as a vapor.

According to one embodiment of the invention, the vapors from the pressure still may be subjected to a refluxing operation in direct contact with fresh charging stock, and the reflux and admixed charging stock positively returned to the still in a manner to insure the subjection of the reflux and admixed charging stock to the cracking conditions maintained in the still before any of the constituents of the reflux and admixed charging stock can again escape as vapor.

In cracking gas oil character stock, for example, for the production of gasoline, according to the present invention, the vapors escaping from the pressure still itself may be subjected to a refluxing operation whereby heavier constituents, such as kerosene vapors or heavier vapors, are separated, and the separated reflux is positively reintroduced into the circulating stream of oil undergoing distillation in the pressure still.

Such refluxed constituents are rapidly re-vaporized under the conditions prevailing in the still, and, having been subjected to the cracking conditions maintained in the still, 5 are relatively refractory. According to the present invention, however, they are reintroduced into the body of oil undergoing cracking in a manner such that they are subjected to the cracking conditions maintained 10 in the still before they can again escape as a vapor.

In subjecting charging stock containing lighter constituents which are rapidly vaporized in the pressure still to the process 15 of the present invention, the charging stock may also be introduced into the circulating stream of oil undergoing distillation in a manner such that it is subjected to the cracking conditions maintained in the still before 20 any of the lighter constituents can escape as vapors. Where fresh charging stock is introduced during the progress of the cracking operation, it may be introduced into direct contact with the vapors in the reflux 25 tower and returned to the pressure still in admixture with the reflux.

The refluxing operation may be carried out at substantially the pressure prevailing in the pressure still, or the refluxing operation 30 may be carried out at atmospheric pressure or at an intermediate pressure lower than that prevailing in the pressure still. Where the refluxing operation is carried out under reduced pressure, a better separation 35 of the heavier vapors may be effected, and the return of lighter constituents, desirable in the pressure distillate, which might otherwise be subjected to objectionable overcracking, may be avoided or reduced while at the same time an increased amount of the 40 heavier constituents which are not desired in the pressure distillate may be returned to the still. For example, in the production of gasoline, the pressure distillate may include 45 a lesser amount of constituents heavier than the desired gasoline product and the amount of gasoline constituents returned and subjected to further cracking may be reduced. Overcracking, which tends to produce additional 50 quantities of incondensable gases and also tends to increase the unsaturation of the pressure distillate to an objectionable degree, is thus avoided or greatly reduced. Both the quality and the yield of the desired 55 product may thus be increased.

The invention is of special value and application in connection with circulatory pressure stills in which the oil in the still is circulated from a bulk supply tank, in which the 60 vaporized constituents are liberated, through a heater in which the oil is heated to the cracking temperature, and back to the bulk supply tank, and especially in circulatory pressure stills of this general type in which 65

the circulation is maintained or assisted by a forcing means such as a pump.

In such a circulatory cracking still, if reflux is returned directly to the body of oil in the bulk supply tank from which the distilled vapors are liberated, as in processes heretofore proposed, all or a large part of the reflux may be again vaporized and escape with the vapors from the still without further cracking, thereby increasing the load 70 on the still without producing any useful result. Moreover, if the reflux is returned to the circulating stream of oil by gravity, the tendency of the reflux to vaporize may even interfere to some extent with the circulation. 75

In the process of the present invention, however, such objections are avoided or largely minimized. In carrying out the present invention in connection with circulatory pressure stills of this type, the reflux is positively introduced into the stream of oil circulating from the bulk supply tank to the heater whereby it is positively forced through the heater and subjected to cracking 80 conditions therein before it can again escape as a vapor. 85

Furthermore, according to this invention, the reflux reintroduced into the pressure still may be employed to assist in maintaining 90 the circulation therein. 95

The invention will be further described in connection with the accompanying drawings illustrating several embodiments of the apparatus of the invention, adapted for the practice of the process of the invention, but it will be understood that the invention is illustrated thereby but not limited thereto. 100

In the accompanying drawings:

Fig. 1 represents, diagrammatically and partly in elevation and partly in section, a pressure still system embodying and illustrating the invention. 105

Fig. 2 is a fragmentary view showing a modified arrangement of the heating element 110 of the still illustrated in Fig. 1, and

Fig. 3 is a view similar to Fig. 1 showing a modified construction and arrangement. 115

The invention is of particular advantage in connection with circulatory tubular cracking stills of the character illustrated. This cracking still is of the general construction illustrated in United States Letters Patent No. 1,285,200 granted to the Sinclair Refining Company November 19, 1918, on the application of Edward W. Isom. 120

The pressure still illustrated in Fig. 1 is made up of the bulk supply tank 1 located away from the heating furnace, the vertical heating tubes 2 arranged in the heating flue of the furnace, and the circulating pipes 3, 4 and 5 connecting the lower and upper ends of the vertical tube with the bulk supply tank and a circulating pump 6 for circulating the oil from the bulk supply tank upwardly 125

through the vertical tubes and back to the bulk supply tank.

Arranged above the bulk supply tank is the reflux tower 7 having a series of baffles 5 therein. The reflux tower is connected with the vapor dome of the bulk supply tank through the vapor line 8. The vapors from the top of the reflux tower escapes through the vapor line 9 to the condenser 10. The 10 condenser discharges into the receiver 11 from which the uncondensed vapors and gases are drawn off through the valved outlet 12 and the liquid condensate through the valved outlet 13. A connection for with- 15 drawing tar during the progress of the cracking operation is shown at 14. Connection 15 is provided for forcing cool oil into the circulating stream of oil through the bearings of the circulating pump. A connection for 20 pumping out and charging the still is shown at 16.

The pressure may be controlled and reduced by means of a regulating valve 24 between the reflux tower and the condenser or 25 by valves 12 and 13 located beyond the receiver. In the latter case, a satisfactory procedure is to withdraw the condensate from time to time or continuously as it collects and to regulate and control the pressure by regulating the escape of uncondensed vapors and 30 gases from the receiver.

A reflux return pump 17 is arranged to receive reflux from the lower end of the reflux tower through connection 18 and to force it 35 through connection 19 into the circulating stream of oil between the circulating pump 6 and the heating tubes. The reflux returned through connection 19 is thus compelled to flow, together with the circulating oil from 40 the bulk supply tank, through the heating tubes where it is heated and subjected to cracking conditions before it can again escape as a vapor from the bulk supply tank, to the reflux tower. The returned reflux may, to a 45 greater or less extent vaporize in the heater, or before it enters the heater as it is admixed with the hot circulating oil, but whether in liquid or vapor phase, it is subjected to the cracking temperature in the heating tubes. 50 The reflux thus forced into the heating tubes absorbs heat and also assists in preventing overcracking of the body of oil circulating within the still. The constituents of the reflux which are vaporized in the heating tubes 55 also assist in maintaining the upward flow of oil therethrough and the circulation of the oil within the still.

By returning the reflux to the lower part 60 of the circulating system, particularly between the circulating pump and the lower end of the heater where a circulating pump is employed, any vaporization of the returned reflux, on contact with the hot circulating oil 65 or in the heater, is employed to maximum ad-

vantage in promoting the circulation within the cracking still.

A by-pass connection 20 with valve 21 is provided for the direct return of reflux from the tower 7 to the bulk supply tank 1, during the initial period of operation, and until the still is brought to cracking conditions of temperature and pressure, reflux may be returned to the bulk supply tank through this connection 20. In normal operation, the by-pass connection 20 may be employed as a safe- 70 guard to prevent reflux, and admixed feed, building up to a level sufficient to choke off the vapor line 8, in case the pump 17 does not take the reflux, and admixed feed, from the lower part of the reflux tower at a sufficient rate. 75

After the pressure still has been raised to the cracking conditions of temperature and pressure, the vapors escaping from the still through connection 8 rise in the reflux tower 7 where they come in direction contact with fresh charging stock introduced through the line 22 to the top of the tower. The heavier constituents in the vapors from the still are thus refluxed, and the reflux and admixed 80 fresh stock are returned from the bottom of the tower by the pump 17 to the circulating stream of oil entering the heating tubes in the still. 85

In operating the pressure still in this way, 90 the circulating oil in the still is circulated from a vaporizing zone, i. e., the bulk supply tank, through a heating zone, i. e., the heating tubes, and back to the vaporizing zone; and reflux from the reflux tower is 95 forced into the circulating oil which is cir- 100 culating from the vaporizing zone to the heating zone and is compelled to pass through the heating zone in admixture with the circulating body of oil before any vaporized constituents can escape from the vapor- 105 izing zone.

In cracking a heavy gas oil charging stock for the production of gasoline, for example, the vapors entering the reflux tower 7 through the vapor line 8 may include, in 110 addition to gasoline constituents, constituents of a light gas oil character as well as kerosene-character constituents. The heavier constituents are refluxed by direct contact with the fresh gas oil charging stock introduced at the top of the tower through connection 22 and the refluxed constituents and admixed feed collect in the bottom of the tower, and are circulated through the heating tubes by the reflux return pump 17. In 115 the heating tubes, the kerosene character constituents may be vaporized and in part cracked and the heavier constituents are in part cracked into lighter products which 120 are vaporized. The vapors liberated in the bulk supply tank thus include cracked products from the fresh charging stock and cracked products from further treatment of 125 the reflux as well as some lighter constitu- 130

ents revaporized without further cracking. The vapors enter the reflux tower from the bulk supply tank and the cycle of the process is repeated. The pressure distillate, including the gasoline character constituents, is withdrawn from the reflux tower as a vapor through the vapor line 9.

In the modified arrangement illustrated in Fig. 2, the returned reflux, and any admixed charging stock, is introduced upwardly into the lower ends of the heating tubes through which the oil in the pressure still is circulating upwardly. The oil from the bulk supply tank is circulated through the connection 4' and upwardly through the heating tubes 2', and the oil from the reflux return pump is forced through connection 19' into the lower ends of the heating tubes 2' through a series of nozzles 23' projecting upwardly into the lower ends of the heating tubes. The oil introduced through the connections 23', including the reflux, vaporizes and is cracked to a greater or less extent in the heating tubes and the resulting vapors assist the circulation. This arrangement of the apparatus is particularly advantageous where no circulating pump or other mechanical circulation is employed and where thermosiphonic circulation is relied upon.

In the apparatus illustrated in Fig. 3, the same or corresponding parts are indicated by the same reference numerals with letter *a* appended thereto. In this apparatus, however, instead of operating the reflux tower at substantially the pressure prevailing in the pressure still, the still pressure is reduced by the pressure control valve 25^a in the vapor line 8^a leading from the pressure still, and the vapors are discharged into the reflux tower 7^a at atmospheric pressure or at a predetermined pressure above atmospheric and lower than the still pressure.

The reflux tower 7^a is shown as of helical construction such that the vapors flow upwardly between the turns of the helical baffle, while the reflux and any fresh feed flow downwardly over the helical baffle. Such a construction permits prolonged contact and heat exchange between the vapors and liquid, both by direct contact of the vapors and liquid and by indirect contact of the vapors with the liquid flowing down over the next higher turn of the helix. This tower is of the general construction and operation described and illustrated in an application of John E. Bell filed April 1, 1924, Serial No. 703,338. It will be apparent that reflux towers of other suitable construction may be employed.

A connection 22^a is provided for introducing fresh oil into direct contact with the vapors in the upper end of the tower 7^a. The condensed vapors and unvaporized feed oil collect at the bottom of the tower in the reflux reservoir 26^a from which they are pumped by the reflux return pump 27^a through the line

19^a to the circulating connection 4^a between the circulating pump and the heating tubes in the pressure still. The vapors from the reflux tower escape through the vapor line 9^a to the condenser 10^a which discharges into the receiver 11^a from which uncondensed vapors and gases are withdrawn through connection 12^a and liquid condensate through connection 13^a. Where the reflux tower is operated at an intermediate pressure higher than atmospheric pressure, the pressure may be reduced and regulated between the reflux tower and condenser by regulating valve 24^a, or the pressure in the condenser may be controlled by valves located beyond the receiver.

The temperature and pressure employed in carrying out the process and in operating the apparatus can be varied with different characters of charging stock. Where ordinary gas oil is employed as the principal charging stock, still pressures in the neighborhood of 90 to 125 lbs. per square inch may be employed; while with lighter oils, such as kerosene for example, higher pressures may be used, for example, up to 300 to 325 lbs. per square inch or even higher. The reflux tower may be operated at the same pressure as that prevailing in the pressure still, or it may be operated at atmospheric pressure or at an intermediate pressure, for example, 25 to 30 lbs. per square inch.

We claim:

1. The improved method of cracking hydrocarbon oils, which comprises maintaining a body of the oil in a bulk supply tank, withdrawing oil therefrom and mechanically forcing the oil so withdrawn through a heater located away from the bulk supply tank and back to the bulk supply tank, maintaining the oil at a cracking temperature throughout the cycle, passing the vapors escaping from the bulk supply tank through a reflux tower, and pumping the reflux from the reflux tower, into the oil circulating from the bulk supply tank to the heater between the mechanical forcing means and the heater.

2. The improved method of cracking hydrocarbon oils, which comprises maintaining a body of the oil in a bulk supply tank, withdrawing oil therefrom and mechanically forcing the oil so withdrawn through a heater located away from the bulk supply tank and back to the bulk supply tank, maintaining the oil at a cracking temperature throughout the cycle, subjecting the vapors escaping from the bulk supply tank to a refluxing operation in direct contact with fresh charging stock to the still and mechanically forcing the reflux and admixed charging stock from the refluxing operation into the oil circulating from the bulk supply tank to the heater between the first mentioned mechanical forcing means and the heater.

3. The improvement in the operation of circulatory pressure stills for cracking hydro-

carbon oils, which comprises pumping the oil from a bulk supply tank upwardly through a vertically arranged tubular heater and back to the bulk supply tank, maintaining the oil at a cracking temperature throughout the cycle, subjecting the vapors escaping from the bulk supply tank to a refluxing operation and mechanically forcing the reflux from the refluxing operation upwardly into the oil circulating from the bulk supply tank through the heater in the lower part of the heater to assist circulation.

4. In an apparatus for distilling hydro-carbon oils under pressure, a pressure still comprising a bulk supply tank and a vertically arranged heater, a connection from the upper part of the heater to the bulk supply tank, and connections including mechanical circulating means between the bulk supply tank and the lower part of the heater whereby oil may be circulated from the bulk supply tank upwardly through the heater and back to the bulk supply tank, a reflux tower, and connections for conducting vapors from the bulk supply tank to the reflux tower, and connections including a pump for injecting reflux from the reflux tower upwardly into the lower end of the heater.

In testimony whereof we affix our signatures.

EUGENE C. HERTEL.
EDWARD W. ISOM.
